FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

1,183,811.

Specification of Letters Patent.

Patented May 16, 1916.

Application filed September 4, 1915. Serial No. 48,971.

To all whom it may concern:

Be it known that I, FREDERIC P. GATES, a citizen of the United States of America, and residing at Hartford, in the county of Hartford and State of Connecticut, have invented a certain new and useful Improvement in Electric Switches, of which the following is a specification.

My invention relates to electric switches and particularly to what are commonly referred to as door switches, the object of my invention being to provide a simplified and improved mechanism of this type.

In the accompanying drawing, Figure 1 is a longitudinal section through a switch in which my invention is embodied in one form; Fig. 2 is a plan of this switch; Fig. 3 is a side elevation of the switch mechanism with the parts in another position; and Fig. 4 is a detached perspective of the switch mechanism elements.

Referring to the drawings, the switch here shown is mounted in a cup-shaped insulating body 10 having at one end an interior barrier 11 between the depressed ledges 12 on which the wire terminals 13 are mounted. Wire holes 14 lead from below to the ledges 12, and the switch terminals 15 have offset ends which are clamped beneath the bases of the respective wire terminals by the securing screws 16.

The switch mechanism is carried by a stamped sheet metal frame 17, having its upper end offset and perforated at 18 to form a guide for the push plug 19 and tapped at 20 to receive a securing screw passing through the usual face plate (not shown). Lugs 21 offset from the bottom of the frame are tapped at 22 to receive the securing screws 23 passing through the bottom of the insulating base 10. Between these lugs lies a downward extension 24 of the frame, slotted at 25. The switch actuating slide or push plate 26, also stamped from sheet metal, is offset at its upper end to afford an attaching seat for the push plug 19 while its lower end has a tongue 27 offset in the opposite direction and provided with a head 28. In the assembled position of the parts the plug 19 extends through the hole 18 in the frame, while the tongue 27 works in the slot 25 with the head 28 spanning the slot on the opposite side of the frame and working in the well 29 formed in the side and base of the body 10 to receive this head

and the downward extension 24 of the frame. From one margin of the push plate 26 extends the lug 30 to engage the ends of the switch spring 31, while from the opposite margin, at a lower point, extends in the same direction the escapement lug 32.

The switch bar 33, also struck from sheet metal, is pivoted at 34 on the pin 35 fast with the standard of the frame 17, and carries at one end the insulated contact piece 36 which spans the switch terminals 15 when the switch is closed. A lug 37 struck at right angles from the switch bar lies between the ends of the switch spring 31 coiled on the pin 35 and spacing the switch bar from the push plate 26 in the assembled mechanism. A detent lug 38, also integral with the switch bar, but bent at right angles thereto, cooperates with the escapement lug 32 on the push plate. The bent end 39 of the switch bar forms a stop lug working between the shoulders 40 formed in one margin of the upright of the frame and limits the extent of oscillation of the switch bar under the influence of the switch spring 31. A heavy return spring 41, mounted on the pin 42 carried by the frame, is normally under tension, one end 43 engaging the bent upper end of the frame while the other end 44 underlies the upper end of the push plate 26 and tends constantly to maintain the latter in its up or out position.

The operation of the mechanism is as follows: In its normal position *i. e.* with the door closed and depressing the push plug 19 in well understood manner, the parts assume the position illustrated in Fig. 1 and the switch is open. As the door opens, the push plug, and with it the push plate 26, moves outward under the influence of the return spring 41. The outward movement of the push plate brings the escapement lug 32 into the path of the detent 38 on the switch bar and the latter is thus held stationary while the lug 32 slides past detent 38 and the switch spring 31 is tensioned by the separation of the lugs 30 and 37. On the escape of lug 38 beneath the lower edge of lug 32, the switch bar, now released, is swung up by the switch spring 31 through the arc limited by the shoulders 40 and engages between the switch terminals 15 thus completing the circuit. A further outward movement of the push plate for a slight distance again slightly tensions the spring 31.

in the same direction and thus holds the switch bar firmly in the "on" position. When the door is again closed, the movement is reversed, the detent lug 38 now bearing against the opposite side of the escapement lug 32 and the return spring 41 being again fully tensioned.

Of course the position of the switch terminal 15 may be reversed to make contact 10 with the switch piece when the push plug 19 is "in" instead of "out", as shown. A full carrying yoke, instead of the ears 45, may be secured by the screws 46, if desired, and in such case the screw taking into the tap 15 20 of the frame would pass through the yoke instead of the face plate as above described.

Various other modifications of the construction will readily suggest themselves to those skilled in the art without departing 20 from what I claim as my invention.

I claim:—

1. An electric switch comprising a slotted sheet metal frame having an offset guide lug, a push plate having a push plug passing through said guide lug and a tongue passing through the slot in said frame and engaging the latter on its opposite face to prevent separation of the parts, a pivoted switch bar, a switch spring for operating 30 the same, an escapement engagement between said push plate and switch bar, and a return spring constantly tending to move said push plate in one direction.

2. In an electric switch of the type described, a sheet metal frame having an upright, supporting lugs offset from the lower end thereof, a slotted downward extension between said lugs, a push plate sliding on one face of said standard and having at its lower end a tongue passing through said slotted extension and engaging said standard on its opposite face, for the purpose described.

3. In an electric switch of the type described, a sheet metal frame having a standard with offset flange at its upper end, a pair of supporting lugs offset from its lower end, and a slotted downward extension between said lugs, a push plate sliding on one face of said standard and having at its upper end a member passing through said top flange of the standard and provided at its

lower end with a tongue passing through said slotted extension and engaging said standard on its opposite face, for the purpose described.

4. In an electric switch of the type described, a sheet metal push plate having at one end a push plug and at the opposite end an offset guide tongue, together with a lug 60 extending from one margin of the push plate and at right angles thereto, for engaging a switch spring and an escapement lug extending in the same direction from the opposite margin of the plate to coöperate 65 with the detent of a switch lever.

5. In an electric switch of the type described, a sheet metal frame plate comprising a standard having a pair of supporting lugs offset from its lower end and a slotted, 70 downward extension between the same to form a guide for a push plate and marginal shoulders in the standard to form stops for an oscillating switch piece.

6. In an electric switch of the type described, a standard offset at its upper end, a push plate sliding on one face of said standard and having an offset at its upper end, a coiled return spring carried by said standard and having one leg engaged with 80 said offset end of the standard and its other leg engaged under tension beneath the offset upper end of the push plate.

7. In an electric switch, a standard having marginal stop shoulders, a push plate 85 sliding on one face of said standard, a marginal lug on said push plate and extending at an angle thereto to form an escapement lug, a pivoted switch lever having a marginal lug angled with relation thereto to 90 form a detent coöperating with the escapement lug on the push plate and an offset end forming a stop lug coöperating with the marginal stop shoulders on the standard, together with a switch spring and an operative engagement between the same and the 95 push plate and switch lever.

In testimony whereof I have signed my name to this specification, in the presence of two subscribing witnesses.

FREDERIC P. GATES.
